(57) **CLAIM**

The ornamental design for an electrical plug-in fragrance dispenser with slot for receiving decorative sheaths, as shown and described.

DESCRIPTION

FIG. 1 is a perspective view of a design for an electrical plug-in fragrance dispenser with slot for receiving decorative sheaths;

FIG. 2 is a front view of the electrical plug-in fragrance dispenser shown in FIG. 1;

FIG. 3 is a rear view of the electrical plug-in fragrance dispenser shown in FIG. 1;

FIG. 4 is a right side view of the electrical plug-in fragrance dispenser shown in FIG. 1;

FIG. 5 is a left side view of the electrical plug-in fragrance dispenser shown in FIG. 1;

FIG. 6 is a top view of the electrical plug-in fragrance dispenser shown in FIG. 1;

FIG. 7 is a bottom view of the electrical plug-in fragrance dispenser shown in FIG. 1; and,

FIG. 8 is a perspective view showing the manner in which a decorative sheath is secured to the electrical plug-in fragrance dispenser shown in FIG. 1.

The dashed broken lines in the drawings represent unclaimed environmental subject matter and form no part of the claim. The dot-dash broken lines depict the boundary of the claim and form no part of the claimed design.
